(57) **CLAIM**

We claim the ornamental design for microscope, as shown and described.

DESCRIPTION

FIG. 1 is a front perspective view of a microscope.

FIG. 2 is a left side elevational view thereof.

FIG. 3 is a right side elevational view thereof.

FIG. 4 is a back side elevational view thereof.

FIG. 5 is a front side elevational view thereof; and,

FIG. 6 is a top plan view thereof.

The broken lines shown represent unclaimed subject matter and form no part of the claimed design.

1 Claim, 6 Drawing Sheets
